ATTORNEY

Victor J. Evans BY

UNITED STATES PATENT OFFICE.

ABRAHAM SCHOCHET, OF NEW YORK, N. Y.

FASTENER AND HANGER.

1,368,579.

Specification of Letters Patent. Patented Feb. 15, 1921.

Application filed May 4, 1918. Serial No. 232,636.

To all whom it may concern:

Be it known that I, ABRAHAM SCHOCHET, a citizen of the United States of America, residing at New York city, in the county of 5 New York and State of New York, have invented new and useful Improvements in Fasteners and Hangers, of which the following is a specification.

This invention relates to pocket books 10 and the like and particularly to those wherein are combined normally concealed or in-closed mirrors, toilet accessories and the like which are adapted to be exposed at times at the convenience of the user.

15 An object of the invention is to combine with a fastener for holding the closing flap of the pocket book or the like closed, means whereby the flap can be expeditiously opened and closed when desired without 20 unduly straining the flap and with an elimination of certain possibility of accidentally tearing the flap during the mentioned operation of opening and closing the same; the said means also serving to enable the user 25 to suspend the pocket book from a suitable support and maintain an open condition thereof in order that the mirror or toilet articles may be conveniently placed on display before the user.

30 With the above and other objects in view which will appear as the nature of the invention is better understood, the same consists in the improved construction and novel arrangements of parts which will 35 hereinafter be fully described and particularly pointed out in the claim.

In the accompanying drawings, has been 40 illustrated, a single and preferred form of the invention, it being, however, understood that no limitations are necessarily made to the precise structural details therein exhibited, but that changes, alterations and modifications within the scope of the claim may be resorted to when desired.

45 Figure 1 is a front view of the pocket book showing the closing flap thereof opened and suspended from a support.

Fig. 2 is a similar view with the flap closed.

50 Fig. 3 is a section taken on line 3—3, of Fig. 2.

The pocket book 5 as herein conventionally illustrated is provided with a closing flap 6, the same being preferably extended from one of the side walls of said pocket book whereby when arranged in an opened position as shown in Fig. 1, it will lie in the same vertical plane with said wall. It is customary to equip pocket books, vanity cases and the like with various toilet articles, mirrors or similar accessories and arrange the same so that they may be displayed before the user when the closing flap is opened. In this instance, a mirror 7 is secured in any suitable well-known 55 manner to the inner face of the closing flap so that when the latter is in the position shown in Fig. 1, the mirror can be readily placed before the user. The wall 8 of the pocket book is provided with a resilient 60 socket 9. The closing flap 6 is provided with a rigid plate 10 which may be of any suitable configuration. I prefer that it be in the form of an oval as shown in Fig. 2. This plate is extended in overlapping engagement against the flap 6 near the free edge thereof and at the center. It is provided with a stud 11 which is extended through the flap 6 and against the inner face of said flap is a washer 12, the same 65 being associated with the stud and fixed thereto. From this washer is extended a head 13 which is adapted to engage in the socket 9 when the flap 6 is closed. The said plate 10 is extended at 14 below the 70 free edge of the flap 6 and it is preferably curved in an outward direction at 15 in order that the finger of the operator can be placed thereunder and the plate canted when releasing the head 13 from its co- 75 acting socket member 9. The said extension 14 is provided with an opening 16 which is adapted to be received by a suitable wall hook 17 as shown in Fig. 1. I, of course, do not wish to limit myself to the application 80 of the invention to pocket books, it being understood that it may be used in connection with travelers' sample cases or the like, so that the article contained therein can be quickly placed on display as desired. 100

What I claim as new is:—

A closure for pocketbooks comprising a

resilient socket carried by the body of the pocketbook, a plate carried by the flap of the pocketbook and having a portion extending beyond the flap, said extended portion being provided with an opening and curved outwardly, a stud projecting from the plate and passing through the flap, a

washer carried by the stud and clamping the flap between itself and the plate, an extension on the stud extending beyond the washer and an enlarged head on said extension for engaging the socket.

In testimony whereof I affix my signature.

ABRAHAM SCHOCHET.
